Marblehead, Mass., assignors to Hygrade Syl-
vania Corporation, Salem, Mass., a corporation
of Massachusetts

Application January 28, 1931, Serial No. 511,762

3 Claims. (Cl. 91—45)

This invention relates to spray guns and similar apparatus for applying coating materials by the spray method.

In using apparatus of this character it is a common practice to protect parts of the work adjacent to that against which the spray is directed by covering such parts with paper, tape, or the like. In some cases, however, this expedient cannot be used satisfactorily, as for example, in internally coating relatively small articles such as electric lamp bulbs.

The present invention deals especially with these conditions. It aims to improve spraying equipment with a view to affording better control of the spray so that surfaces adjacent to those to be coated can be protected from the spray without the necessity of covering them with some protecting material.

The nature of the invention will be readily understood from the following description when read in connection with the accompanying drawing, and the novel features will be particularly pointed out in the appended claims.

In the drawing,

25 Figure 1 is a perspective view of an apparatus embodying features of this invention;

Fig. 2 is a plan view of the spray nozzle shown in Fig. 1;

Fig. 3 is a perspective view of the end portion 30 of the nozzle and adjacent parts of the apparatus shown in Figs. 1 and 2; and

Fig. 4 is a side elevation of a somewhat different embodiment of the invention.

Referring first to Figs. 1, 2 and 3, the apparatus there shown comprises a spray gun 10 which includes a control lever or trigger 12, a relatively long shank 13, and a spray head or nozzle 14. The nozzle includes two air outlets 15, Fig. 3, located at opposite sides of another outlet 16 for the paint, lacquer, or other coating material, the two air outlets 15 being directed toward each other and toward the paint outlet 16. So far as these features are concerned the spray gun is of a common commercial type and it may be constructed, 45 arranged and operated in the usual manner.

A gun of this construction produces a fan-like spray which scatters considerably at the edges. In order to cut off the spray more sharply, the spray gun shown is equipped with a shield 18 which may conveniently be made of sheet metal and preferably includes a split clamp 19 by means of which it is detachably secured to the shank 13 of the spray gun, the split portions of the clamp being secured together by a screw or bolt 20. This 55 shield is so shaped and positioned, as will be evi-

dent from an inspection of the drawing, that it intercepts or cuts off sharply one edge of the fan-shaped spray.

In using this apparatus to internally coat a portion of an electric lamp bulb, as for example 60 the rounded bowl portion 2, Fig. 1, the spray gun is inserted in the bulb in approximately the relationship illustrated in Fig. 1, and the bowl is revolved about its own axis while the spray is directed against its inner surface. The shield 18 so 65 controls one side of the spray that the coated area terminates at a fairly definite edge. A sufficiently clean line of demarcation thus is provided between the coated and the uncoated areas to satisfy the demands of the trade. At the same time this result is produced without using an internal covering 70 for the portions of the bulbs which are not to be coated. Usually the bulbs are heated during the spraying operation so that the coating dries very 75 quickly.

Some of the coating material intercepted by the shield 18 will collect on the shield and run down to the lower edge where it tends to drop off. In order to prevent this action the lower edge of the shield is bent or rolled over to form a trough 80 21 extending along the lower edge, this trough serving to catch and hold the coating material that otherwise might drop from the edge of the shield.

A somewhat different arrangement is illus- 85 trated in Fig. 4 in which the spray gun is so mounted that its shank 13 occupies approximately an upright position. This gun also is equipped with a shield 24, much like the shield 18, and secured to the shank 13 in the same manner. The 90 shield tapers, with its larger end extending upwardly, and its edges are rolled or turned inwardly so that they catch and guide any drip into a tube 25 which extends along the shank 13 of the spray gun and leads into an annular trough 95 or receptacle 26 secured to the gun at the lower end of the shank 13. Another tube 27 leads the drip from this receptacle to any desired point of discharge.

This shield operates to cut off the edge of the 100 spray in the same manner as does the shield 18 and thus to afford much better control of the coating material at the edge or margin of the coated area.

In addition to using a shield like those shown 105 at 18 and 24 which control the spray at one side only, a second shield such as that indicated at 28, Fig. 4, can be used to control or cut off the opposite side of the spray, and such a device may be used either alone or in conjunction with a 110

shield like that shown at 18 or 24. The shield 28 is provided with a split clamp 30 to secure it detachably to the shank 13 of the spray gun.

Such an arrangement as that shown in Fig. 4, 5 without the shield 28, is particularly adapted for use in a machine for internally coating lamp bulbs to produce a so-called "white bowl" effect. The shield 28 may be used without the shield 24 in internally "skirt coating" a lamp bulb, while 10 the two may be used together where it is desired to coat a band only of the skirt or cone of the bulb.

While we have herein shown and described preferred embodiments of our invention, it will 15 be understood that the invention may be embodied in other forms and that the apparatus may be used for other purposes without departing from the spirit or scope of the invention.

Having thus described our invention, what we 20 desire to claim as new is:

1. In an apparatus for applying coating material to the inner surfaces of electric lamp bulbs, the combination of a spray gun constructed to be inserted in an electric lamp bulb through the 25 neck thereof, said gun having a nozzle adapted to produce a fan-like spray and to direct said spray laterally away from said gun and against the inner walls of the bulb, a shield mounted on said gun and shaped and positioned to cut 30 off one edge of said spray and to combine the coating to a predetermined area having a sharply defined boundary, and a trough at one edge of said shield for catching any liquid which may run down the face of the shield.

35

2. In an apparatus for applying coating material to the inner surfaces of electric lamp bulbs, the combination of a spray gun constructed to be inserted in an electric lamp bulb through the neck thereof, said gun having a nozzle adapted 80 to produce a fan-like spray and to direct said spray laterally away from said gun and against the inner walls of the bulb, a shield mounted on said gun for cutting off one edge of said spray and to confine the coating to a predetermined area having a sharply defined boundary, and means for conducting liquid which collects on and runs down the face of the shield backwardly along the shank of said gun.

3. In a device for applying a coating having a sharply defined boundary to the inner surface of a bulb having an elongated neck and a spherical bowl portion, the combination of a spray gun having an elongated shank, a discharge end for insertion through the neck portion of the bulb, 90 said gun having a discharge nozzle inclined to said shank for producing a fanlike spray mainly at an angle to the longitudinal axis of the bulb and against the inner wall of said bowl portion, and a shield carried by said gun laterally adjacent 95 said nozzle for intercepting the spray to confine it to a predetermined area on the inner surface of said bowl, said area having a sharply defined boundary.
